(57) **CLAIM**

The ornamental design for an image distance control device, as shown and described.

DESCRIPTION

FIG. 1 is a front perspective view of an image distance control device showing the new design;

FIG. 2 is a front perspective view thereof with an unclaimed cellular telephone inserted therein;

FIG. 3 is a rear perspective view thereof;

FIG. 4 is a front side view thereof;

FIG. 5 is a rear side view thereof;

FIG. 6 is a right side view thereof;

FIG. 7 is a left side view thereof;

FIG. 8 is a top view thereof; and,

FIG. 9 is a bottom view thereof.

The broken lines in the Drawings depict environmental subject matter and form no part of the claimed design.
